UNITED STATES PATENT OFFICE.

ALBERT MARTIN, OF NEWARK, NEW JERSEY.

EXPANSION-SPIKE.

1,024,904.

Specification of Letters Patent. Patented Apr. 30, 1912.

Application filed January 24, 1912. Serial No. 673,114.

To all whom it may concern:

Be it known that I, ALBERT MARTIN, a subject of the King of Hungary, residing at Newark, in the county of Essex and State of New Jersey, have invented certain new and useful Improvements in Expansion-Spikes, of which the following is a specification, reference being had therein to the accompanying drawing.

10 This invention relates to expansion spikes, and the objects of my invention are, first, to provide a spike with clamping jaws that can be easily and quickly expanded to lock the spike in a body; second, to provide a 15 spike that can be advantageously used for retaining a rail upon a tie; third, to provide an expansion spike that can be readily removed from the body in which it is mounted, and fourth, to accomplish the above results 20 by a mechanical construction that is durable and highly efficient for the purposes for which it is intended.

With the above and other objects in view, the invention resides in the novel construction, combination and arrangement of parts 25 to be hereinafter specifically described and then claimed.

Reference will now be had to the drawing, wherein:—

30 Figure 1 is an elevation of a portion of a tie, partly broken away and partly in section, illustrating one of the spikes in side elevation, Fig. 2 is a perspective view of a spike, and Fig. 3 is a longitudinal sectional view of the same.

A spike in accordance with this invention 35 comprises a cylindrical body 1 having a longitudinal bore 2 extending from one end thereof to the opposite end. The upper end 40 of the body 1 has a clamping head 3 upon the inner side thereof and a stop lug 4 upon the opposite side, the stop lug 4 being removed from the upper end of the body, and said lug is adapted to engage in a tie or 45 other body 5 and limit the movement of the spike body in an opening 6 provided therefor in the tie 1. The upper end of the spike body 1 is enlarged to provide a head 7 and diametrically opposed sides of said head are 50 cut away and flattened, as at 8, whereby a suitable instrument, as a crow bar, can be placed in engagement with the head of the spike for removing the same from the opening 6.

55 Secured to diametrically opposed sides of the spike body 1, at the lower end thereof,

by screws 9 or other fastening means are the upper ends of resilient locking arms 10, the lower ends of said arms having jaws 11. These jaws provide shoulders 12 that engage an annular shoulder 13 formed by enlarging the lower end of the opening 6.

Rotatably mounted in the bore 2 of the spike body 1 is a pin 14 that has the lower end thereof tapered, as at 15 to provide clearance for a movement of the arms 10. Secured to the lower end of the pin 14 by a transverse pin 16 is a cross head 17. The cross head is substantially oval in plan and has flattened ends to engage the flattened inner sides 18 of the jaws 11. The pin 15, adjacent to the cross head 17, is provided with staples or eyes 19 and extending through said staples or eyes are curved check members 20 having hook-shaped ends 21. The check members 20 are carried by the inner sides of the resilient locking arms 10, and these members limit the rotative movement of the pin 14, said members determining when the cross head 17 is in engagement with the jaws 11 and the arms 10 expanded to lock the spike body within the opening 6.

The upper end of the pin 14 is provided with a rectangular head 22, said head having a recess 23. Arranged within the recess 23 is a compression spring 24 that engages the inner side of a latch 25 pivotally connected by a pin 26 to the head 22. The lower end of the latch extends into a keeper notch 27 formed in the head 8, said latch locking the pin relatively to the spike body. By pushing inwardly upon the upper end of the latch 25, the lower end of the latch is shifted out of the notch 27 and the pin head 22 can be rotated a quarter of a revolution to shift the cross head 17 crosswise relatively to the arms 10, thereby releasing the jaws 11 and allowing the jaws to recede and assume a closed position that permits of the spike body 1 being removed from the opening 6.

The expandable spike is made entirely of light and durable metal and can be made of various sizes and used for other purposes than that herein shown and described.

What I claim is:—

1. An expansion spike comprising a body, resilient arms carried by the lower end thereof and provided with jaws, a pin rotatably mounted in said body, a cross head carried by the lower end of said pin and adapted to engage the jaws of said arms for

expanding said arms, a head carried by the upper end of said pin, and means carried by said head for locking said pin relatively to said spike body.

- 5 2. An expansion spike comprising a body, resilient arms carried by the lower end thereof and provided with jaws, a pin rotatably mounted in said body, a cross head carried by the lower end of said pin and adapted to engage the jaws of said arms for expanding said arms, a head carried by the upper end of said pin, means carried by said head for locking said pin relatively to said spike body, and means carried by said 10 resilient arms and engaging the lower end of said pin for limiting the movement of said pin.
3. An expansion spike comprising a body, a clamping head carried by the upper end 20 thereof, resilient locking arms carried by the lower end thereof, a pin rotatably mounted in said body, a cross head carried by the lower end of said pin and adapted to contact with and expand the lower end of said arms, a head carried by said pin, and means including a pivoted latch carried by said head for locking said pin relatively to said body.
4. An expansion spike comprising a body, a clamping head carried by the upper end 25 thereof, resilient locking arms carried by the

lower end thereof, a pin rotatably mounted in said body, a cross head carried by the lower end of said pin and adapted to contact with and expand the lower ends of said arms, a head carried by said pin, means including a pivoted latch carried by said head for locking said pin relatively to said body, and means including check members carried by said arms for limiting the movement of said pin relatively to said body. 35

5. An expansion spike comprising a body, a clamping head carried thereby, a check lug carried by said body, resilient arms carried by the lower ends of said body, jaws carried by the lower ends of said arms, a pin rotatably mounted in said body, a cross head carried by the lower end of said pin and adapted to engage said jaws to expand the lower end of said arms, a head carried by the upper end of said pin, a spring pressed latch 50 carried by said head for locking said pin relatively to said body, and means carried by the lower ends of said arms for limiting the movement of said pin in said body. 45

In testimony whereof I affix my signature in the presence of two witnesses.

ALBERT MARTIN.
